UNITED STATES PATENT OFFICE.

MAURICE GOUDARD AND MARCEL MENNESSON, OF NEUILLY-SUR-SEINE, FRANCE.

MOTORCYCLE.

1,371,783.

Specification of Letters Patent. Patented Mar. 15, 1921.

Application filed June 4, 1919. Serial No. 301,742.

To all whom it may concern:

Be it known that we, MAURICE GOUDARD and MARCEL MENNESSON, both engineers, and citizens of the French Republic, and residing 5 both in Neuilly-sur-Seine, Department of Seine, France, have invented certain new and useful Improvements in Motorcycles, of which the following is a specification.

This invention relates to motor cycles.

10 It has for its principal object the construction of the frame of motor cycles in a more practical manner than has been the case hitherto.

It consists essentially in so constructing 15 the frame of a motor cycle, with the use of a single tube that the frame will have the general appearance of the frame of a lady's motor cycle, that is to say shall be open; shall comprise between the wheels of the 20 motor cycle a horizontal or slightly inclined portion, suitable for supporting the luggage carrier and the foot rests; shall comprise at the right of the rear motive wheel a curved portion surrounding the motor and serving 25 as means for attaching this latter, and shall terminate at the rear extremity in a branch which may be eventually bent into a plane perpendicular to the central plane of the back wheel and be adapted for the 30 support of the saddle.

The invention includes in addition to this principal construction, certain other features which will be more particularly described hereafter.

35 It includes more particularly certain constructional embodiments as well as the application of the said features and more particularly and as new industrial products, motor cycles comprising the said features as 40 well as special parts suitable for their construction.

It will in any case be well understood with the assistance of the following description and the accompanying drawing which however 45 ever as will be clearly understood are given merely by way of example.

Figures 1 and 2 of the drawings show respectively in side elevation and in rear elevation a motor cycle constructed according 50 to the invention.

Fig. 3 is a section on line 3—3 Fig. 1

but, to a larger scale than the preceding figures, illustrating a detail of construction of the motor cycle.

Fig. 4 is a plan view of the tubular frame. 55 According to the invention and more particularly according to the methods of carrying the same into effect illustrated on the drawings, we construct the motor cycle in the following or in some analogous manner. 60

a is a steering fork, supported by the front wheel *b*. *c* is a motor supported through the intervention of its casing *c*¹ by the back wheel *d* of the motor cycle, the two wheels being preferably plain. In the casing of 65 the motor is mounted the axle *d*¹ of the back wheel *d* carried by suitable bearings, the said axle being connected to the motor shaft by suitable transmission gearing, for instance gearing corresponding in the arrangement 70 described in the application for French Patent No. 486324, filed in the same names on October 4, 1916.

e is a tubular framework which is preferably given the general shape of the frame 75 of a lady's motor cycle, that is to say an open shape.

It may be for instance formed from a single tube connecting together the steering fork *a* and the back wheel *d*. With this object in view we preferably connect the said tube at the end to the rear portion of the socket *a*¹ of the steering fork *a*, for instance in the median plane of the rear wheel. We cause it first to descend in a straight line at 85 a short distance from the front wheel, and we then extend it horizontally or at a slight inclination in the same plane, so that we can mount on this portion a luggage carrier *f* and a foot rest *g*, the latter being constituted 90 for example by two U-shaped irons parallel to one another stretching over the tube *e* and clamped to the upper portion of the latter by means of stirrup shaped clamps *g*¹ embracing the lower portion of the said tube, 95 the upper arms of the stirrups passing vertically through the said U-shaped irons and the luggage carrier, which latter is fixed to the foot rests by means of nuts *g*² screwing on to screw threaded extremities of the arms 100 *g*¹ of the stirrups.

In the neighborhood of the forward por-

tion of the back wheel, the tube e is bent twice at right angles in a horizontal plane, in such a way that the said tube extends beyond the bend at the side of the back wheel 5 in a plane parallel to the median plane of the said back wheel. It is then bent again in the said parallel plane so as to embrace the lower and rear portion of the casing c^1 of the motor. It is then continued into a straight 10 portion at an angle directed toward the interior of the motor cycle, where it terminates at the height at which the saddle h is to be supported, after having given it a last bend in a horizontal direction and at right angles 15 so as to bend it toward the interior of the motor cycle. The saddle is attached in any appropriate manner at the end of the tube e and in order that the weight of the person mounted upon the motor cycle shall counter- 20 balance substantially the weight of the portion of the motor and of the said tube projecting on one side of the machine, we displace to a suitable amount the said saddle to the opposite side to that on which the projecting parts are located. The motor c is 25 attached by means of its casing c^1 , for instance by using stirrup shaped pieces c^2 or pieces of some analogous shape extending around the outer portion of the tube e , the 30 arms being screw threaded at the ends for the reception of nuts c^3 screwing against shoulders carried by the casing. An exhaust tube c^4 is provided in such a position that it extends backward at the side of the 35 driving wheel. The said motor may comprise a single cylinder located between two branches of the V formed by the tube, or two cylinders arranged as a V may be located in the same position, or better still two op- 40 positely directed cylinders may be employed, the latter cylinders being arranged at the side of the plane.

The tube e may with advantage constitute the reservoir for the liquid fuel, in which 45 case we make it of appropriate section and provide it with a filling orifice c^1 . We also prefer it to contain the different controlling mechanisms which are necessary for the operation of the motor and for manipulating 50 the brakes. The controls are preferably provided in the ordinary manner with flexible connections i of the Bowden type which enter the tube e in the neighborhood of the handle bar a^2 , and which come out of it in 55 the neighborhood of and below the saddle h , where they are bent around and directed toward the different organs to be controlled. The entry and exit openings of the said flexible connections are located above the maximum level reached by the liquid fuel. 60

The constant level j or auxiliary reservoir for the liquid fuel may with advantage be made in one with the tubular reservoir e and may be connected in any suitable manner with the feed conduit for the motor. 65

With this end in view, we may substitute for one of the stirrups c^2 fixing the casing of the motor to the said tube, the chamber of the constant level which is attached to the lower portion of the tube e by means of bolts j^1 70 connecting the said chamber to the casing, and the float j^2 is so arranged that its needle j^3 regulates the supply of the liquid fuel through an orifice e^0 provided at the lowest portion of the tubular reservoir e . 75

In some cases it is advantageous, in place of forming the lower branch of the tube e , so that it is horizontal, to give it a certain inclination toward the carburetor so as to counterbalance the effect of the slopes. 80

As will be readily understood, the invention is not limited in any way to the methods of carrying the same into effect or to the particular constructional details which have been described; on the contrary, it includes 85 all modification.

Having now particularly described and ascertained the nature of our said invention and in what manner the same is to be performed, we declare that what we claim is:— 90

1. In a motorcycle, a framework comprising a single continuous tube connected at one end to the front fork head and so formed as to provide at the other end a U-shaped portion adapted to partially surround and to support the engine. 95

2. In a motorcycle, an engine, a frame comprising a tube connected at one end to the front fork head, thence extending downward, thence horizontally and having its other end so shaped as to partially surround the engine and to constitute a support therefor, and extending upward and being so formed at its extremity as to provide a saddle post. 105

3. In a motorcycle, an engine, a frame comprising a tube connected at one end to the front fork head, said tube being adapted to serve as a liquid reservoir, an inlet for the liquid fuel in the front end of said tube, 110 said tube being so formed at its other end as to partially surround and support the engine, and an auxiliary reservoir and float feed device connected to and in communication with said tube adjacent the engine. 115

4. In a motorcycle, an engine, a front fork head, a tube connected to said front fork head and adapted to constitute an open frame for the cycle, said tube extending from the front fork head in a downwardly inclined direction, thence horizontally in a direction out of the median plane of the wheels, thence rearwardly parallel to the median plane of the wheels, thence upward in said parallel plane, thence horizontally 120 and upwardly, whereby said tube is adapted to partially surround and support the engine and terminate in a saddle post. 125

5. In a motorcycle, a driven wheel, an engine adjacent said wheel and operatively 130

connected thereto, a continuous tubular member constituting the frame of said cycle, said tubular member being so formed as to partially surround said engine, a front fork 5 head connected to one end of said tubular member, and means for connecting said tubular member to said engine.

In testimony thereof we have hereunto set our hands in presence of the subscribing witness.

MAURICE GOUDARD.
MARCEL MENNESSON.
